UNITED STATES PATENT OFFICE.

CHARLES AUGUSTUS BUTLER, OF OKMULGEE, OKLAHOMA.

OIL-WELL PUMP.

1,175,599.

Specification of Letters Patent. Patented Mar. 14, 1916.

Application filed January 26, 1915. Serial No. 4,480.

To all whom it may concern:

Be it known that I, CHARLES A. BUTLER, a citizen of the United States, and a resident of Okmulgee, in the county of Okmulgee and State of Oklahoma, have invented a new and Improved Oil-Well Pump, of which the following is a full, clear, and exact description.

My invention relates to oil-well pumps wherein the gas in the well is utilized for driving the oil from the well.

The object of the invention is to provide a simple, inexpensive, valveless pump which is automatic in its action and which will require little or no attention, as there are no parts apt to get out of order.

With the above and other objects in view, the nature of which will more fully appear as the description proceeds, the invention consists in the novel construction, combination and arrangement of parts as herein fully described, illustrated and claimed.

In the accompanying drawing, forming part of the application, similar characters of reference indicate corresponding parts in the view, which is a longitudinal cross section of a well equipped with a pump embodying my invention.

The gas present in an oil well, if at a sufficient pressure, will force the liquid out of the well; but when the pressure of the hydrostatic column of the liquid in the well is greater than the pressure of the gas where it enters the well, the gas will only raise the column of liquid to a certain height and be unable to force the same out; and the gas will filter little by little through the liquid column out of the well.

The purpose of my invention is to utilize the gas which is unable to force the liquid column out of the well, so that a smaller column of liquid will be forced by said gas out of the well, although it is normally unable to force the hydrostatic head above the gas entrance out.

Referring to the drawings, 1 represents an oil well into which a well casing 2 is inserted, the foot of which casing rests above the gas stratum which superposes the oil stratum. The gas coming from the gas sands is normally unable to raise the column of liquid 3 resting above the gas sand out of the casing 2, although it might raise it to a certain height within the casing. To cause the gas coming from the gas sand to

drive the liquid present in the well casing therefrom, I provide a pump which consists of a gas bell 4, in the shape of a tube of a diameter slightly less than the diameter of the casing 2. The length of the gas bell will vary according to the depth of the well and the height of the liquid column present in the well casing. The lower end of the gas bell is open and is brought to a level with the foot of the casing 2, that is, substantially to the level of the gas stratum. The upper end of the gas bell is closed by a plug 5, which plug has a central aperture threaded at its extremities. The threaded portion of the bore of the plug located within the gas bell receives a tube 6 which extends through the entire length of the gas bell and out of the same into the oil stratum, whereat said tube is provided with perforations giving access to the oil from the stratum. The other threaded portion of the bore of the plug 5 receives a tube 7 which projects through the head 8 of the casing 2 and is directed to a reservoir 9. The tube 6 is also provided with an aperture 10 which is located within the gas bell 4 and adjacent the plug 5.

When my pump is lowered into a well, the gas will accumulate in the gas bell until it is full. The oil in the well casing 2 will be at the same level as the oil in the tube 7. The gas present in the bell will be at a pressure equal to the gas pressure at the foot of the bell. The gas pressure at the foot of the bell is equal to the gas pressure in the gas stratum plus the hydrostatic column between the opening 10 and the foot of the bell, and this will be the pressure of the gas at the opening 10. When this pressure is higher than the hydrostatic column within the tube 7, said column will be driven by the gas pressure from the bell into the reservoir 9. The column of liquid displaced by the gas from the tube 7 will be replaced by oil through the perforations in the tube 6; and, again, as the gas in the bell reaches a pressure higher than the column of liquid above it, it will drive the same out from the tube 7. This intermittent rise and fall of gas pressure within the bell 4 will cause a pulsation of liquid from the tube 7 into the reservoir 9. The sequence of pulsations of liquid will vary in accordance with the reestablishment of pressure within the gas bell 4. That is to say, it will depend on how

fast the gas sand can replace the gas which has escaped through the opening 10 from the gas bell.

It will be noted that although the gas in 5 the well is unable to force out of the well the hydrostatic column located above the gas sands, the same gas pressure will easily force out the hydrostatic column located above the opening 10 within the tube 7; 10 and if the supply of gas is large, the pulsations will be continuous and a substantially continuous flow of oil from the well through the pipe 7 will result. The fluid in the pipe 6 cannot retract back into the well through 15 the perforation because the pressure is greater at the perforation than it is at any higher point; consequently, there is no necessity for using any check valves, thus eliminating the possibility of contrivances 20 which will easily get out of order.

The casing 2 is preferably provided with an opening 11 to prevent any gas pressure within the casing above the liquid column therein.

25 From the foregoing description, taken in connection with the accompanying drawing, the advantage of the construction and operation of my device will be readily understood by those skilled in the art to which 30 the invention pertains; and while I have described the principle of operation, together with the structure which I now consider to be the best embodiment thereof, I desire to have it understood that the pump 35 shown is merely illustrative and that such changes may be made as are within the scope of the appended claims.

Having thus described my invention, I claim as new and desire to secure by Letters Patent:

1. In a device of the class described, a gas bell, a tube within the bell projecting through the top thereof and having an opening within the bell adjacent the top 45 of the bell.

2. In a device of the class described, an elongated gas bell, a tube within the gas bell projecting through the lower and upper ends thereof, said tube having an aperture 50 within the bell.

3. In a device of the class described, a

tube having a closed top, a second tube within the first extending beyond the lower end and through the top of the first tube, said second tube having an opening positioned within the first tube in proximity to the top substantially as and for the purpose set forth.

4. In a device of the class described, a tube, a plug closing one end of said tube, a second tube passing through said plug, projecting above the same and beyond the open end of said first tube, said second tube having perforations at the end projecting beyond the open end of the first 65 tube, and an opening within said first tube adjacent the plug substantially as and for the purpose set forth.

5. In a device of the class described, a tube, a plug closing one end of said tube, said plug having a threaded bore, a second tube within said first tube having one end thereof in threaded engagement with the plug, the other end of said second tube projecting out of the open end of the first tube, 75 said projecting end having apertures on the lateral surface thereof, and a third tube engaging the threaded bore of the plug and forming a continuation of said second tube, said second tube having an opening adjacent the end in threaded engagement with the threaded bore of the plug substantially as and for the purpose set forth.

6. The combination of a well casing having an oil and a gas flow at the lower end 85 and open at the top with a tube closed at the top and submerged into the oil of the well, and a second tube within the first extending beyond the lower end into the oil section of the well, and through the top of the first 90 tube out of the well, said second tube having an opening in proximity to the closed top of the first tube, substantially as and for the purpose set forth.

In testimony whereof I have signed my name to this specification in the presence of two subscribing witnesses,

CHARLES AUGUSTUS BUTLER.
